UNITED STATES PATENT OFFICE.

GREGORY BROWN AND ALBERT TURNER, OF WORCESTER, MASSACHUSETTS,
ASSIGNORS TO NORTON COMPANY, OF WORCESTER, MASSACHUSETTS, A COR-
PORATION OF MASSACHUSETTS.

MACHINE-TABLE-REVERSING MECHANISM.

Application filed June 29, 1921. Serial No. 481,178.

To all whom it may concern:

Be it known that we, GREGORY BROWN and ALBERT TURNER, citizens of the United States of America, residing at Worcester, in the county of Worcester and State of Massachusetts, have invented certain new and useful Improvements in Machine-Table-Reversing Mechanisms, of which the following is a full, clear, and exact specification.

10 This invention relates to driving and reversing mechanisms and is particularly intended for gradually starting and stopping the reciprocable table of a machine tool without serious shocks and driving it at a normal rate between reversals.

It is one object of our invention to utilize ordinary gears and associated parts with their attendant advantages in a simplified type of reversing mechanism which will 20 positively start and stop the reciprocable table of a machine tool gradually and without material shock.

It is a further object of our invention to provide a device of this type with a releasable locking connection between the reciprocable table and the cam operating mechanism whereby the cam will be forced to travel with the table during both the starting and the stopping movements and will be 30 returned to and released in a central position for normal operation of the machine.

With these and other objects, as will be apparent from the following disclosure, our invention resides in the combination of parts 35 set forth in the specification and covered by the claims appended hereto.

Referring particularly to the drawings, in which like numerals indicate like parts, we have there shown one form of our invention 40 in which:

Figure 1 is a front elevation, partly broken away, of a grinding machine base including our invention;

Fig. 2 is a section substantially on the line 45 2-2 of Fig. 1, with parts of the mechanism removed for the sake of clarity of illustration;

Fig. 3 is a side elevation, partly in section, illustrating particularly the cam slide operating lever;

Fig. 4 is a top plan view with the table removed of a portion of the reversing mechanism;

Fig. 5 shows in a top plan view a detail of the reversing dog mechanism; and

Figs. 6 and 7 are diagrammatic sketches illustrating the driving gear and cam mechanism in two end positions as compared with the central position shown in Fig. 1.

In the practice of our invention we utilize the principle that if a driven gear and a driving member are moved relative to each other in the same direction as or opposite to that of the periphery of the gear while the driving member is being otherwise moved normally, the motion of the driven gear is affected thereby. This relative movement may be between two gears, either in mesh or connected by a chain, which are mounted to move peripherally relative to each other, while the driver moves normally. By controlling this peripheral motion, such as the rolling of two gears on their peripheral pitch line of contact, by means of a cam or other suitable mechanism to produce a gradually accelerated relative movement until the motion of revolution equals that of rotation, the rotary motion of the driven gear is gradually neutralized and may be brought from full speed to rest. Similarly if the outer member is initially rolling along the periphery of the other gear and its motion of revolution is gradually retarded while it is rotated at a uniform rate, the inner driven gear is gradually accelerated from rest to full speed. If these gears, which may be arranged for external or internal driving contact, are connected one with the machine table and the other through a reversing mechanism with a power shaft, the table may be reciprocated, a cam controlling mechanism being interposed to cause the initial gradual acceleration or retardation at each reversal.

As a specific embodiment of our invention, we have illustrated a machine tool having a reciprocable table 10 of standard construction mounted on V and flat ways 11 and 12 respectively on a suitable base 13. The driving mechanism therefor, which may be mounted on the base, or in a removable box 14 as illustrated, comprises a driven gear 15 operatively connected with the table, here shown as meshing directly with a rack 16 fixed on the under side of the table 10. In order to rotate gear 15, a driving gear 20 is supported in mesh therewith by

means of arms 21 and 22 pivoted on the axis of gear 15. As shown, they may be revolubly mounted on the shaft 23 which supports the driven gear 15, this shaft being 5 suitably mounted in bearings in the box 14. The arms 21 and 22 are secured together at their outer extremities by pins 25 and carry the driving gear 20 suitably mounted therebetween on the shaft 26.

10 The gear 20, which is revoluble about the gear 15, may be rotated at a substantially uniform rate irrespective of its motion of revolution by means of suitable flexible driving connections. These may comprise 15 universally jointed telescoping members driven by a reversing mechanism. As shown, these parts comprise a socketed member 30 universally connected to the end of shaft 26. A telescoping member 31 20 slidably fitting within the socket of the part 30 is similarly universally connected with the shaft 32 which is mounted in bearings in the box 14. Keyed to this shaft 32 is a driving gear 33, which in turn meshes 25 with a similar gear 34 keyed to the shaft 35 mounted in the lower portion of the box. This shaft 35 is driven alternately in opposite directions by suitable reversing mechanism which may comprise a main driving 30 shaft 36 having the bevel gears 37 and 38 loosely mounted thereon and adapted to be connected to the shaft by means of a shiftable clutch member 39 keyed to the shaft 36 and adapted to engage a clutch portion 35 on the end of one of the bevel gear members 37 or 38, as is well known in this art. These gears 37 and 38 are in mesh with a gear 40 mounted on the end of shaft 35 so that, depending upon which way the clutch is 40 thrown, the driving gear 20 will be rotated in one direction or the other and consequently the table traversed as desired.

In order to obviate the shocks incident to starting and stopping the table, we provide a positively acting cam controlling mechanism which causes the driving gear 20 to assume a secondary motion along the periphery of the gear 15 while rotating continuously and thereby affect the driving 45 action of the latter gear. It will be obvious that if the small driving gear 20 while rotating normally is revolved about gear 15 in a direction opposite to that which it tends to drive the latter first at the full rate 50 of driving and then be gradually retarded in its peripheral motion until it is stationary, the driven gear will be gradually brought from zero to full speed. To this end, we provide a cam member shown as a 55 slide 45 supported in slideways 46 on the front of the machine. A cam slot 48 of the desired shape and dimensions is provided in this slide 45 and a cam follower 60 therefor, here shown as a pin 50, is rigidly supported on the side of the arm 21 opposite

the pitch line of the two gears, passing through a suitable opening in the side of the box 14. By means of this construction the position of the driving gear 20 relative to the gear 15 is determined by the location 70 of the cam follower 50 in the slot 48.

While we may move and control the cam slide by various mechanisms, we preferably employ a lever 52 pivoted at 53 on the front of the machine which has a handle 54 at 75 its upper end for manual manipulation of the cam slide. This lever 52 is connected by a link 56 with the slide 45, it being noted that the cam slot might be located directly in the lever, but with its curve slightly 80 changed as will be apparent. The lever 52 is normally held in a vertical position and the cam slot centralized relative to the cam follower, as shown in Fig. 1, by means of a spring pressed plunger 57 mounted within a 85 hollow box 58 projecting from the rear of the handle 52. The lower end of the plunger is made V-shaped to fit in a similarly shaped groove 59 in a block 60 fixed on the front of the machine, this block having a curved top surface for the plunger to ride along during movement of the handle. The plunger is held normally in engagement with the block by means of a spring 61 located within box 58 and positioned by 90 the adjustable nut 62 threaded into the upper portion of the opening in the box, the spring bearing at its lower end on the flange 63 on the plunger and normally pushing downwardly thereon.

The table of the ordinary machine tool is adapted to be traversed through a variable distance. This is accomplished by means of the usual adjustable dogs 65 and 66 which may be clamped in any desired position by means of a T member 67 slidably mounted in the T slot 68 in the edge of the machine table, in accordance with the usual practice. In the simplified construction illustrated, we have shown the cam slide as 100 moved and controlled by movement of the table. To this end we provide means to connect the lever 52 periodically to the table. This may comprise a lug 70 projecting rearwardly from the handle 52 which is adapted to be engaged by one or the other of the table dogs. In order that the cam operating handle 52 may be held firmly in engagement with the dogs throughout the complete extent of the reversing operation, 110 we provide each dog with a projecting lug 72 separated from the main body of the dog by a groove 73 and the parts are so constructed and arranged that the lug 72 on the dog may pass beneath the lug 70 115 on the handle and then as the handle is moved forward by the travelling dog, the lug 70 on the handle will move downwardly 120 into the slot 73. Then when the direction of table movement is reversed the lug 72 125 on the handle will move upwardly into the slot 73. Then when the direction of table movement is reversed the lug 72 130

will retain its hold on the handle and move it backward to substantially a vertical position, as shown in Fig. 1, where the spring pressed plunger can centralize the handle 5 and lock for the normal driving movement of the table.

The direction of rotation of the various parts may be reversed by a suitable load and fire mechanism, a simplified construction 10 of which is illustrated in Fig. 1. As there shown, the slidable clutch member 39 which is keyed to the shaft 36 is engaged by a yoke member 75 mounted in a groove 76 of the slidable clutch member. This yoke member 75 has upwardly projecting end portions 77 and 78 slidably mounted on the rod 79 which is suitably supported on the machine and surrounded by the springs 80 located between the upright portions or 15 lugs 77 and 78. Pivoted locking fingers 82 and 83 are mounted on the rod 79, each having a downwardly projecting shoulder 84 adapted to engage the outer side of one of the projecting lugs and to hold the clutch 20 yoke 75 in locking engagement with one or the other of the gears 37 or 38. As shown, the finger 82 is locked behind the left-hand lug 77. In order to throw the clutch, the member 85 rigidly fixed to the 25 slide 45 is provided with arms 86 which are adapted to engage one or the other of the pivoted fingers 82 or 83 and by means of cam surfaces on these cooperating parts to lift the finger out of engagement with 30 the lug 77. The member 85 has a further projection 87 which surrounds the rod 79 and engages the spring thereon so that upon movement one way or the other it compresses the spring on one side and stores up 35 energy until a finger is moved to release the lock, whereupon the clutch is forcibly and quickly thrown in the desired direction.

It will now be evident in view of the 40 above disclosure that when the cam slide is held stationary the mechanism will drive the work table at a normal and uniform rate, the axis of the driving gear 20 being in a horizontal plane with the axis of the driving gear 15 and the cam follower 50 being located in the central portion of the cam slot 48. This slot is made in a substantially S-shape, as illustrated, with the central portion of the S approximately horizontal, so that the normal upward or 45 downward thrust of the pin 50 on the cam slot will engage this horizontal portion and prevent peripheral movement of the driving gear. In order to bring the table gradually to a stop it is necessary that the driving gear 20 travel at first slowly and at an increasing rate peripherally along the 50 driven gear 15 until the clutch has been thrown. To accomplish this purpose the cam slot is so shaped as to comply substantially with the law of falling bodies as

modified by practical considerations met with in designing and operating the machine. As illustrated, the outer halves of the slot are substantially parallel with the periphery of the driven gear 15 and the intermediate portions are so formed that the pin 50 will first be moved at a very slow rate peripherally of gear 15 adjacent the central position and gradually accelerated as it travels outwardly.

The construction and purpose of these parts will be more fully understood from a consideration of the operation of the machine. Assuming that the table is moving in the direction of the arrow in Fig. 1, 55 the machine will therefore operate at a continuous rate until the dog 66 has moved over to the left and struck the lug on the arm 52. The clutch still being connected for driving to the left, the dog 66 will 60 move the arm and therefore the slide 45 toward the left. This will cause the cam following pin 50 to travel along the upper portion of the cam slot 48 and so carry the small gear 20 with it. At first the vertical 65 component of the travel of this pin is small and the driving action of the gear 20 will be neutralized only to a slight extent, but as the pin goes up the slot it is gradually 70 assuming a line substantially parallel with the periphery of the gear 15 and the gear 20 is rolling along its periphery at an increasing rate, thus neutralizing more and more its driving action. The effect of this 75 is to slow down the traverse of the table gradually until, when the pin 50 has 80 reached the outer stretch of the cam slot 48 all driving action on gear 15 has been 85 neutralized.

In suitable timed relation to the table 90 movement, as is best determined by practical adjustment of each machine depending upon the inertia of the movable parts, the load and fire mechanism, which has been 95 compressing the left-hand portion of the spring 80, lifts the finger 82 and releases the clutch, causing it to throw quickly to the 100 left to engage the opposite gear and thus reverse the direction of the driving gear 20. This operation may be so timed that the 105 table will be just stopped as the direction is reversed, or the clutch may be thrown before the cam follower has reached the outer portion of the cam path. Reversing the 110 rotary movement of gear 20 results in a downward thrust on the cam follower which at first moves at full speed without starting the table and then gradually transmits more 115 and more thrust on the table dog and the gear 15 to start the table towards the right. As the cam follower approaches the horizontal portion of the cam slot, the horizontal 120 thrust transmitted through the lever 52 and the table lug 72 lessens and the lever 125 is permitted to stop in its central driving 130

position. The handle 52 remains locked to the table during the starting operation because the lug 70 is held in the slot 73 behind the lug 72 on the table dog and is thus 5 returned to a vertical position where the plunger 57, which has formerly been forced out of its locking groove, now returns to this groove to hold the pin 50 centrally located in the cam slot, after which the table 10 is again driven at its normal full speed. When the clutch is next thrown, the cam follower 50 traverses the lower reaches of the cam slot and the same operations are gone through to stop and start the table 15 gradually. The driving gear 20 will thus oscillate between the upper and lower positions shown in Figs. 6 and 7, depending upon the direction of movement of the table.

20 Having thus described our invention, what we claim as new and desire to secure by Letters Patent is:

1. A driving and reversing mechanism for machine tool tables comprising a driver 25 and a driven member in peripheral rolling contact and operatively connected with the table, means to move the driver uniformly and traverse the table at a normal rate for an indefinite period and mechanism effective 30 at the period of reversal to impress upon the driver a secondary movement peripherally around the driven member which accelerates its driving action and gradually starts the table into motion.

35 2. A driving and reversing mechanism for reciprocable bodies comprising a rotary gear operatively connected with said body, means including a driver to rotate the gear at a uniform rate, and mechanism effective 40 to revolve said driver and gear relative to each other peripherally at an increasing rate to neutralize the driving action and bring the table gradually to a stop.

45 3. A driving and reversing mechanism for machine tool tables comprising a rotary driven member operatively connected with said table, a driving member therefor, means to move said driving member at a normal rate and cam controlled mechanism 50 effective to impress an accelerated secondary motion upon said driving member around and in a direction opposite to that of the periphery of the driven member to gradually retard the rotation of the latter.

55 4. A driving and reversing mechanism for machine tool tables comprising a driven gear operatively connected with said table, a driving gear meshing therewith, one of 60 said gears being mounted for revolution about the axis of the other while rotating, and cam controlling mechanism effective to control said revolving motion while rotating the driver at a normal rate and cause the table to be stopped and started gradually.

65 5. A driving and reversing mechanism

for the reciprocable table of a machine tool comprising a rotary driven member operatively connected with the table, a rotary driver revoluble about the axis of said driven member, and positively actuated mechanism to rotate said driver and simultaneously revolve it at a decreasing rate to start the table gradually into motion.

6. In a machine tool having a reciprocable body, a driven gear operatively connected with said table, a rotatable driving gear revoluble peripherally in mesh with said driven gear, means to rotate said driving gear in opposite directions, and means to revolve the rotating driving gear at a 70 decreasing rate to start said table gradually into motion and thereafter drive it at a uniform rate before reversal.

7. A driving and reversing mechanism for machine tool tables comprising a driven gear operatively connected with the table, a driving gear meshing therewith, means to support said driving gear for a partial revolution about the axis of the driven gear, means to rotate said driving gear in opposite directions at a uniform rate, and cam controlling mechanism effective to limit the peripheral motion of the driving gear about the driven gear to start and stop the table 80 gradually and thereafter to drive it at a uniform rate between reversals.

8. In a machine tool having a reciprocable table, a driven gear operatively connected with said table, a driving gear meshing with and mounted to swing about the axis 90 of said driven gear, means to rotate said driving gear in opposite directions, and means controlled by movement of the table to swing said driving gear at an increasing and then a decreasing rate about said driven gear to stop and start the table gradually and thereafter to drive said table at a uniform rate.

9. In a machine tool having a reciprocable table, a driven gear operatively connected therewith, a driving gear meshing with and mounted to swing about the axis of said driven gear, means to rotate said driving gear in opposite directions irrespective of its movement of revolution, and means comprising a movable cam device and a releasable control member operated by the table effective to cause the driving gear to move at an increasing and then a decreasing rate 110 in opposite directions along the periphery of the driven gear to neutralize the effect of the normal driving action and stop and start the table gradually.

10. In a machine tool having a reciprocable table, a driven gear operatively connected therewith, a driving gear supported for a partial revolution about the axis of the driven gear and in mesh therewith, a movable cam member, a cam follower revoluble with said driving gear, and means operated 125

- by said table effective to move said cam member and the follower when the direction of table movement is to be reversed, said cam member and follower being shaped and 5 arranged to cause the driving gear to move peripherally of the driven gear at a decreasing rate to start the table gradually into motion and thereafter drive the table at a uniform rate.
- 10 11. In a machine tool having a reciprocable table, a driven gear operatively connected with said table, a driving gear supported for a partial revolution about the axis of said driven gear and in mesh therewith, reversing mechanism including a clutch to rotate the driving gear in opposite directions, a cam member movable by said table, a cam follower cooperating therewith revolute with the driving gear, said cam 15 being shaped and arranged to permit movement of the driving gear peripherally of the driven gear at a gradually increasing rate, and means operated by the table to move said cam member and retard movement of the table and thereafter throw the clutch to reverse the direction of reciprocation.
12. A driving and reversing mechanism for a machine tool table comprising driving and driven members, means controlled by the table to move one member relative to the other to partially neutralize the driving action and cause the table to start gradually into motion, and a locking device opera- 20
- tively connecting said means and the reciprocable table during the starting action and releasing said connection thereafter for driving the table at its normal rate. 35
13. In a machine tool having a reciprocable table, a driven member operatively connected therewith, a driving member therefor, and means controlled by movement of the table to impress upon the normal action between the driving and driven members a relative secondary motion which will cause the table to start gradually, including a movable cam controlling device and a locking member operatively connecting said device with the table during the starting action and releasing it therefrom for the normal 40 45
- indefinite traversing movement. 50
14. In a machine tool having a reciprocable table, a driven gear operatively connected therewith, a rotary member to drive said gear, cam controlling mechanism effective to impress a secondary motion upon said rotary member to neutralize its driving action and causes the table to start and stop gradually, and a locking device connecting said mechanism with the table for 55 controlling the starting and stopping action which automatically releases such connection for the normal indefinite traverse of the table between reversals. 60
- Signed at Worcester, Massachusetts, this 27th day of June, 1921.
